UNITED STATES PATENT OFFICE.

MEAD PEIRCE, OF EAST PALESTINE, OHIO, ASSIGNOR OF ONE-FOURTH TO FRANKLIN J. FRANCIS AND ONE-FOURTH TO DAVID J. DAVIS, BOTH OF EAST PALESTINE, OHIO.

HANGER BRACKET FOR TROLLEY-WIRE GUARDS.

Application filed June 3, 1927. Serial No. 196,388.

This invention relates to hanger brackets for trolley wire guards and aims among other objects to provide an improved bracket for supporting guard rails or boards in mines.

In the accompanying drawing,

Fig. 1 is a side elevation showing a series of brackets embodying my invention applied to a mine trolley wire;

Fig. 2 is a top plan view of the brackets shown in Fig. 1;

Fig. 3 is a central sectional view of one of the brackets shown on an enlarged scale;

Fig. 4 is a perspective view of the bracket shown in Fig. 3;

Fig. 4^a is a perspective view of one of the guard board flanges; shown in Figs. 3 and 4; and

Fig. 5 is a sectional view of a bracket showing a modified form of guard holding attachment for my bracket.

Referring particularly to the drawing and to the embodiment of my invention illustrated in Figs. 1 to 4, I have there shown my brackets applied to trolley wire insulators 10 which are anchored in a mine ceiling or roof 11. However, they may be secured at intervals between the insulators, as indicated at 12.

Herein, the brackets are shown as being made of sheet metal so that they may easily be made by cutting and stamping operations. In the present instance, they are substantially channel-shaped having downwardly depending flanges 13 integral with a web 14 which has an opening 15 adapted to receive a lag screw or expansion bolt 16 to which the web is clamped between washers 17.

To support safety guard rails or boards 18 at the sides of the trolley wire as required by law, I have shown the lower ends of the flanges 13 as being bent outwardly at right angles to provide ledges 19 and then upwardly to provide board retaining flanges 20 so that the boards 18 may be inserted edgewise into the trough-shaped grooves produced by these bends.

To secure the boards against accidental displacement, I have shown struck-up projections 21 formed by producing angular slits in the ledge portions and bending the sharp ends at right angles to the sheet. These projections are preferably formed so that they may be driven into the edges of the boards or rails with their planes extend-

ing lengthwise of the grooves or along the natural grain of the wood.

Referring to Figs. 3 and 4, I have also shown means to hold the upper edges of the boards or rails against lateral displacement. To avoid the necessity for and expense of securing the boards by bolts, I provide flanged clips 22 shown as being channel-shaped, the ends of one flange presenting reversely bent ears 23 adapted to engage the opposite parallel edges of the flanges 13. In Figure 4, the flanges 13 near their lower ends have notches 24 to receive the ears so that the clips may be put on very quickly. These clips have struck-out nailing projections 25 adapted to be driven across the grain of the boards to hold them securely against longitudinal displacement.

In Fig. 5, I have shown a modified form of the clips comprising a Z-shaped piece of sheet metal or Z bar 26 adapted to be secured by bolts 27 inserted through vertical slots 28 in the flanges 13. It is not necessary to provide the nailing projections when this type of clip is used because the clips may be firmly secured in place.

From the foregoing description, it will be seen that my improved brackets can be made very cheaply; that safety guards or boards may be applied to them without having to drill bolt holes and insert bolts. Moreover, the cost of the labor for installing them is greatly reduced.

Obviously the present invention is not restricted to the particular embodiment thereof herein shown and described. Moreover, it is not indispensable that all the features of the invention be used conjointly, since they may be employed advantageously in various combinations and subcombinations.

What I claim is:—

1. A guard hanger bracket for mine trolley wires comprising, in combination, a channel shaped member having flanges adapted to straddle the trolley wire and a web portion to be rigidly secured relative to roof; means integral with the lower ends of the flanges to hold the guards; and clip means cooperating with the flanges above their ends to hold the guards against displacement.

2. A guard hanger bracket for mine trolley wires comprising a channel-shaped member having outwardly and upwardly bent ends providing trough-shaped grooves to re-

ceive the guards; and struck-out nailing projections formed thereon.

3. A guard hanger bracket for mine trolley wires comprising a channel-shaped member having outwardly and upwardly bent ends providing trough-shaped grooves to receive the guards; and flanged clips slidable on the flanges of the channel-shaped member cooperating with the grooves to secure the guards in place.

4. A guard hanger bracket for mine trolley wires comprising in combination, a substantially channel-shaped member having

angularly bent ends to receive the lower edges of guard boards; flanged clips presenting reversely bent ears adapted to engage the opposite edges of the channel flanges said channel flanges having notches to permit the clips to be inserted and guided thereon; and struck-out projections on said clips and said angularly bent portions to secure the boards against accidental displacement.

In testimony, that I claim the foregoing as my own, I have hereto affixed my signature.

MEAD PEIRCE.
